GAME BOARD

Richard L. East, 408 Fusco Ave., Modesto, Calif.

Filed Aug. 18, 1960, Ser. No. 61,819

Term of patent 14 years

(Cl. D34—5)

FIG. 1.

FIG. 2.

FIGURE 1 is a plan view of a Game Board showing my new design, and

FIGURE 2 is a sectional view taken on line 2—2 of FIGURE 1.

The dominant features of my design reside in the portions shown in full lines.

The characteristic features of my design for the game board disclosed reside in the centrally disposed cross figure within the Geneva cross outline and the series of four semicircular indentations equally spaced in alignment extending outwardly from the end of each leg of the Geneva cross and running parallel with the channeled corners, all as shown.

I claim:

The ornamental design for a Game Board as shown and described.
